UNITED STATES PATENT OFFICE.

CLARENCE ALOY BOOKER, OF DANTE, VIRGINIA.

FLUID-PUMP.

1,369,382.

Specification of Letters Patent. Patented Feb. 22, 1921.

Application filed January 19, 1920. Serial No. 352,300.

To all whom it may concern:

Be it known that I, CLARENCE A. BOOKER, a citizen of the United States, residing at Dante, in the county of Russell and State 5 of Virginia, have invented certain new and useful Improvements in Fluid-Pumps, of which the following is a specification.

This invention relates to a fluid pump of the rotating impeller type, and is especially adapted for mine water handling in view of the fact that its construction embraces but a single moving part readily adjustable to compensate for wear due to grit, acid water and other sludge material 15 encountered in mine pumping conditions.

The invention has, as a further object, the provision of a pump which is so constructed that the impeller acts to uniformly accelerate the velocity of the water from the 20 inlet to the discharge side of the pump.

A further feature of the invention is the mounting of the impeller in a pump casing having the inlet and discharge heads separable from the pump casing body, which latter part is a relatively simple casting requiring but little machining and hence may be cheaply replaced and the same inlet and discharge heads used with a new pump casing body. The impeller of the pump forms 30 another novel feature of the invention in that the fluid pumped is uniformly accelerated in the passage from end to end of the impeller by reason of the fact that the impeller is of a type having a continuous helical rib of increasing pitch from the inlet 35 to the discharge end thereof.

Another object of the invention resides in the provision of a pump which is outside packed and is so constructed that the packing 40 is accessible without disturbing the pump connections or setting.

Figure 1 is a side elevation of the pump; Fig. 2 is a longitudinal section;

Fig. 3 is a transverse section on the line 45 3--3 of Fig. 2;

Fig. 4 is an enlarged vertical section longitudinally of one of the stuffing boxes, and

Fig. 5 is a side elevation of the impeller removed from the casing.

50 In detail: The pump comprises a pump casing body A having a base 1 and a pump casing body 2 which is provided with a passage 3 tapering from the inlet toward the discharge end. The base 1 is strengthened by the ribs 4 and may be bolted in place by suitable lag screws or other means 5 as shown. The in-

let and discharge ends of the pump casing body 2 are flanged as shown at 6 and 7 for purposes to be hereinafter set forth. The impeller consists of a shaft 8 having keyed 60 as at 9 or otherwise secured thereto an impeller 10 having the continuous helical rib 11 of gradually increasing pitch from the inlet to the discharge end so as to uniformly accelerate the velocity of the fluid pumped 65 toward the discharge end thereby making it possible to pump against a relatively large head of water.

At the intake end the flange 7 of the pump casing body is bolted to the flange 12 of an 70 intake head 13 which incloses the intake end portion of the impeller shaft 8 and also is provided with an intake passage 14 adapted to receive the threaded end of an intake pipe 15, said intake head being secured in place 75 by bolts 16 extending through the flanges 7 and 12 with a suitable packing ring 17 therebetween, which bolts are tightened up by means of the nuts 18. The intake head is cut out as shown at 19 to receive a bearing collar 20 which seats against the shoulder 21 in said cut-out and a spring 22 bears against said collar 20 and also receives one side 23 of a stuffing box the other side of which is flanged as shown at 24 to 80 fit over the side 23 of said stuffing box and both sides are beveled to accommodate the packing 25, as shown. Adjustment of the stuffing box for tightening on the shaft 8 is secured by means of a stuffing box face plate 90 26 bearing against the outer end of the stuffing box and adjusted by means of bolts 27 screwing into the intake head. The end 28 of the intake head is bored out or cored out as shown to receive the said face plate 26 95 and the outer end of the said intake head is flanged as at 29 to receive an end bearing 30 having the bearing bushing 31 and the flange 32 which bolts up against the flange 29 and seats against the packing ring 33 and 100 is held in place by bolts 34 and nuts 35. The extreme end of the shaft carries one half of a flanged coupling 36 which is bolted to a similar half 37 by means of bolts 38 and nuts 39 for the purpose of direct connection of said shaft to the shaft 40 of a suitable prime mover such as an electric motor or the like. The outlet or discharge head of the pump is formed similarly to the intake head in that the body 41 thereof bolts 110 up against the flange 6 by means of bolts 42 and makes a tight joint therewith by

2

reason of the fact that it seats on a suitable packing ring 43 and the shaft 8 extends through a collar 44 seating on a shoulder 45 and which has a spring 46 bearing there-
 5 against and the end of which spring receives one half 47 of a stuffing box, the other half of which is indicated at 48 and has a flange extending over the opposite side of the stuffing box and both halves being beveled to
 10 receive the packing 49, the stuffing box being tightened up against said packing by the face plate 50 screwed down into position by the bolts 51, the discharge head 41 being cored out or bored out as shown at 52 to re-
 15 ceive said face plate and having a flange 53 which is secured by bolts 54 and nuts 55 to a flange 56 of a thrust bearing head to be later described, a suitable packing ring 57 being placed between the two flanges. The
 20 thrust bearing head 58 is extended from the flange 56 and carries a bearing bushing 59 which has a shoulder 60 receiving the ball race 61 accommodating the balls 62 and which coöperate with a second ball race 63
 25 held thereagainst by a bearing plate 64 and a nut 65 on the end of the shaft 8 and to which access may be had by means of the cover plate 66 held in place by bolts 67 and nuts 68 so as to protect the bearing and
 30 form a lubricant inclosure, a washer or packing ring 69 being provided between the two members forming the head in order to make the same tight so that lubricant will not escape. The arrangement of the stuffing
 35 boxes at each end of the pump is such, as will be noted, that access may be had to the same without disturbing the impeller and inasmuch as the construction is such that the pressure of the water in all instances is
 40 against the springs of said stuffing box it will be noted that there is very little likelihood of any leakage past said stuffing boxes. The stuffing boxes may be adjusted by

simply removing the members 30 and 41 without disturbing the pump connections. 45

I claim:

1. A pump comprising a conical casing having its ends open and provided with flanges, inlet and discharge heads having flanges secured to said first named flanges, a shaft extending through said heads and provided with a conical impeller arranged within said casing and having a helical rib of gradually increasing pitch toward the discharge end, said heads being provided with 55 chambers having shoulders, bearing collars having shoulders contacting with said first named shoulders, stuffing boxes within said chambers and provided with interfitting sections and packing, glands adjustably connected to said heads, and closure plates at the ends of said chambers for concealing said stuffing boxes and provided with bearings rotatably receiving said shaft.

2. A pump comprising a conical casing 65 having its ends open and provided with flanges, inlet and discharge heads having flanges secured to said first named flanges, a shaft extending through said heads and provided with a conical impeller arranged 70 within said casing and having a helical rib of gradually increasing pitch toward the discharge end, said heads being provided with chambers having shoulders, bearing collars having shoulders contacting with 75 said first named shoulders, stuffing boxes within said chambers and provided with interfitting sections and packing, glands adjustably connected to said heads, closure plates at the ends of said chambers for concealing said stuffing boxes and provided with bearings rotatably receiving said shaft, and one end of said shaft.

In testimony whereof I affix my signature. 85
 CLARENCE ALOY BOOKER. [L. s.]
